US00D983757S

(12) **United States Design Patent** (10) **Patent No.:** **US D983,757 S**
(45) **Date of Patent:** **** Apr. 18, 2023**

(54) **REMOTE CONTROL WITH ICON**
(71) Applicant: **HUNTER FAN COMPANY**,
Memphis, TN (US)
(72) Inventor: **Seth Aaron Wood**, Bartlett, TN (US)
(73) Assignee: **Hunter Fan Company**, Memphis, TN
(US)
(**) Term: **15 Years**
(21) Appl. No.: **29/669,331**
(22) Filed: **Nov. 7, 2018**
(51) **LOC (14) Cl. 14-03**
(52) **U.S. Cl.**
USPC **D13/168**

(57) **CLAIM**

The ornamental design for a remote control with icon, as shown and described.

DESCRIPTION

FIG. 1 is a top view of a remote control with icon according to my new design;

FIG. 2 is a top view of the remote control with icon of FIG. 1, with the icon shown in a different position on the remote control;

FIG. 3 is a top view of the remote control with icon of FIG. 1, with the icon shown in a different position on the remote control;

FIG. 4 is a top view of the remote control with icon of FIG. 1, with the icon shown in yet another position on the remote control;

FIG. 5 is a top view of the remote control with icon of FIG. 1 with a left portion lined to be shaded with yellow color and a right portion lined to be shaded with blue color, shown on a remote control similar to that of FIG. 1;

FIG. 6 is a top view of the remote control with icon of FIG. 2 with a left portion lined to be shaded with yellow color and a right portion lined to be shaded with blue color, shown on a remote control similar to that of FIG. 2;

FIG. 7 is a top view of the remote control with icon of FIG. 3 with a left portion lined to be shaded with yellow color and a right portion lined to be shaded with blue color, shown on a remote control similar to that of FIG. 3; and,

FIG. 8 is a top view of the remote control with icon of FIG. 4 with a left portion lined to be shaded with yellow color and a right portion lined to be shaded with blue color, shown on a remote control similar to that of FIG. 4.

Portions of the remote control shown in broken lines form no part of the claimed design. FIGS. 5-8 are lined for color.

1 Claim, 8 Drawing Sheets
